CLAIM

The ornamental design for a cart for paper, as shown and described.

DESCRIPTION

FIG. 1 is a right side elevational view of a cart for paper showing my new design;

FIG. 2 is a left side elevational view thereof;

FIG. 3 is an end elevational view thereof with side panels raised in an alternate position;

FIG. 4 is a top plan view of FIG. 3; and

FIG. 5 is an enlarged fragmentary elevational view thereof showing the self locking mechanism in collapsed condition as in FIG. 1.

FIG. 1

FIG. 2

FIG. 3

FIG. 5

FIG. 4
